H. Locke,
Cork Machine.

No 24,471.

Patented June 21, 1859.

UNITED STATES PATENT OFFICE.

HARVEY LOCKE, OF SOUTH BOSTON, MASSACHUSETTS.

CORK-MACHINE.

Specification of Letters Patent No. 24,471, dated June 21, 1859.

To all whom it may concern:

Be it known that I, HARVEY LOCKE, of South Boston, in the county of Suffolk and State of Massachusetts, have invented a 5 new and Improved Machine for Cutting Corks for Bottles and other Vessels; and I do hereby declare that the following is a full, clear, and exact description of the same, reference being had to the annexed drawing, making a part of this specification, in which—

Figure 1, is a longitudinal vertical section of my invention, taken in the line x, x , in Fig. 3. Fig. 2, is a transverse vertical section of ditto, taken in the line y, y , in Fig. 3. Fig. 3, is a horizontal section of ditto, taken in the line z, z , in Fig. 1.

Similar letters of reference indicate corresponding parts in the several figures.

20 This invention consists in a novel arrangement of clamps, knives, adjustable mandrel and head, arranged for joint operation, substantially as hereinafter shown, whereby corks for bottles and other vessels may be 25 formed or cut very expeditiously, in a perfect manner, and by an automatic operation throughout.

To enable those skilled in the art to fully understand and construct my invention, I 30 will proceed to describe it.

A, represents a rectangular framing which may be constructed in any proper manner to support the working parts of the machine.

B, is a shaft which is placed transversely 35 on the upper part of the framing A, and has a wheel C, attached to its outer end, said wheel, as will be presently shown, performing the offices of both a crank wheel and a cam. To the outer side of the wheel C, one 40 end of a connecting rod D, is attached, and the opposite end of said rod is connected to a knife stock E, which is fitted on a guide rod F, and is moved back and forth thereon, by the rotation of wheel C. The knife 45 stock E, has four knives a, b, c, d , attached to it. The knives a, b , are in a horizontal plane and have oblique or diagonal cutting edges, and at the front and back end of the stock, as shown clearly in Fig. 3. The knife 50 c , is also in a horizontal plane and is placed at the side of the stock, as shown also in Fig. 3. To the under side of the knife stock the cutter d , is attached, which is of tubular form, see Figs. 1, and 2.

55 G, is a sliding or reciprocating plate

which is placed on the upper part of the framing A, and has a clamp H, fitted in it. This clamp H, is formed of two curved jaws e, e , which work on pivots f, f , and are closed by means of a bent lever g , and a wedge-shaped projection i , which is in line with the space between the lower ends of the levers. The lever g , has its fulcrum pin j , in the plate G, and a rod I, is attached to its upper end, said rod being connected to a 60 slide rod J, which is operated by an irregular-shaped groove k , in the inner side of the wheel C, and in which groove k , one end of the rod J, is fitted. The form of the groove k , is shown clearly in Fig. 1, the rod J, is 65 shown in Fig. 3. In the inner side of the wheel C, there is also an irregular groove l , in which one end of a lever K, is fitted; m , is the fulcrum pin of lever K, and to said lever one end of a rod L, is attached the opposite ends of said rod being connected to a lever M, which works on a fulcrum pin n , in said frame. The upper end of the lever M, is just above the top of the framing A, and a jaw n' , is at its upper end, said jaw 70 being directly opposite a corresponding stationary jaw o , attached to the framing.

The outer end of the lever K, is forked and is fitted in a groove in a mandrel N, which is fitted or has its bearings in uprights p, p , attached to a bar O, which is placed in the upper part of the framing A, and secured therein by a fulcrum pin g , and set screw r . The mandrel N, is rotated by a 75 belt s , from the wheel C, said belt passing over guide pulleys t . A head u , is attached to the inner part of the bar O, said head being in line with the end of the mandrel N. On the inner part of the bar O, there is also placed a wheel v , the periphery of which 80 may be coated with emery or any suitable substance to serve as a sharpener. Similar wheels w, w , are also placed in bars a', a' , directly above the wheel v , all the wheels w, w, v , being driven by belts b' , from pulleys c' , on a shaft P, which is rotated by the same belt s , that rotates the mandrel N.

The plate G moves in a transverse direction on the framing A, and it is operated in one direction, that indicated by arrow 1, in Fig. 3, by a lever Q, which is actuated by projections d' , on the inner side of the wheel C, see Figs. 1 and 3, and is operated in the other direction, as indicated by arrow 2, by a lever R, which is actuated in consequence of 105 110

a projection e' , on its upper surface fitting in oblique grooves f' , in the under side of the knife stock E.

On the upper side of the framing A, and 5 directly above the jaws u', o , a vertical spout S, is attached, the interior of which is of rectangular form and of such dimensions as to receive proper sized slabs or bars of cork.

The operation is as follows. The cork 0 is previously cut in slabs or bars of such size that will fit in the spout S. Motion is given 5 to the wheel C, by any proper means and the lower end of the bar or slab T, shown in red, in the spout S, rests on a stop g' , attached to 10 the stationary jaw o . At each vibration of the knife stock E, a piece of cork, a^* , is cut 15 from the slab or bar T by the cutters a, b , alternately, the lower part of the slab or bar T, being grasped between the jaws u', o , just previous to each cut, so that the pieces a^* , 20 are held by the jaws u', o , as they are cut from the slab or bar, the jaw n' , being actuated by the rod I, slide J, and groove k, in 25 wheel C,—while the cutters a, b , are in the act of cutting, or immediately after, the 30 plate G, is moved in the direction of arrow 2, by lever R, so that the clamp H, will be below the piece of cork between the jaws u', o . The pieces a^* of cork, as they are cut 35 from the slab or bar T, are of rectangular form but they are rounded or have their angles removed by the tubular knife or cutter d, which has a cutting edge at each end and act immediately after each knife a, b . 40 After the pieces are cut from the slab or bar by the knives a, b , and rounded by the knife d, the clamp H, grasps them, the levers e, e, of which are actuated or closed by the 45 action of the wedge-shaped projection i, of the lever g, the latter being actuated by the rod I, slide rod J, and groove k, in wheel C. The pieces are then by the movement of the 50 plate G, in the direction of arrow l, which movement is given it by lever Q, brought directly in line with mandrel N, and the head u, and said mandrel is then by the action of lever K, thrown forward to press into the piece of cork between the jaws or levers e, e, of clamp H, and 55 rotate the same, the clamp H, opening by the action of lever g. As the piece of cork is rotated by the mandrel N, the knife c, passes along and cuts it in perfectly coni-

cal form, the pieces of cork, being in fact turned, the conical form being due to the 55 inclined position of the mandrel N, relatively with the cutting edge of the knife c, and this inclination may be made greater or less, according to the degree of taper desired to be given the corks, by giving the 60 bar O, a greater or less inclination in the framing. The piece of cork that is cut from the slab or bar T, at one movement of the knife stock E, is turned at the succeeding movement. The knife c, is kept in perfect 65 working order by the sharpeners v, w, w, between which it passes at each forward movement.

As the finished corks fall from the mandrel N, which occurs as the mandrel N, is 70 drawn back, the corks fall on a lever b*, and actuate an index c*, that traverses over a dial plate d*, see Fig. 1, and registers the number of corks cut by the machine.

Having thus described my invention, what 75 I claim as new and desire to secure by Letters Patent, is—

1. The employment or use of a reciprocating knife-stock E, when provided with necessary knives and arranged in combination with a rotating mandrel N, traversing clamp H, and feed spout or trough S, so that as the knife stock moves back and forth, pieces of cork a^* , will be cut from the bar or slab T, and said pieces turned in suitable 85 conical form, substantially as described.

2. I claim, in connection with the reciprocating knife-stock E, attaching the mandrel N, and head u, to an adjustable bar O, fitted in the framing A, and arranged substantially as described so as to admit of the adjusting of the pieces of cork a^* , more or less obliquely with the knife c, and vary the taper of the corks as may be desired. 90

3. I claim placing the clamp H, in a 95 reciprocating plate G, operated by the lever Q, from the wheel C, and the lever R, from the reciprocating knife stock E, substantially as shown and described for the purpose of giving the traversing movement to 100 said clamp to convey the pieces of cork a^* , from the jaws u', o , to the mandrel N.

HARVEY LOCKE.
